Primary Examiner — Elizabeth Albert

(57) CLAIM

The ornamental design for a marker, as shown and described.

DESCRIPTION

FIG. 1 is a front elevational view of a marker showing my new design, the rear elevational view being a mirror image of the front elevational view;

FIG. 2 is a left side view thereof, the right side view being a mirror image of the left side view;

FIG. 3 is a top plan view thereof;

FIG. 4 is a bottom plan view thereof;

FIG. 5 is a perspective thereof; and,

FIG. 6 is a perspective view of the marker with its cap detached.
